US0D1017633S

(12) **United States Design Patent** (10) Patent No.: **US D1,017,633 S**
(45) Date of Patent: ** Mar. 12, 2024

(54) **DISPLAY PANEL WITH GRAPHIC USER INTERFACE**

(71) Applicant: **Coupa**ng Corp., Seoul (KR)

(72) Inventors: **Jonathan Chung**, Seoul (KR); **Seong Eun Kim**, Seoul (KR); **Sang Bin Hyun**, Seoul (KR)

(73) Assignee: **Coupa**ng Corp., Seoul (KR)

(**) Term: **15 Years**

(21) Appl. No.: **29/780,083**

(22) Filed: **Apr. 22, 2021**

(30) **Foreign Application Priority Data**

Oct. 23, 2020 (KR) 30-2020-0050880

(57) **CLAIM**

The ornamental design for a display panel with graphic user interface, as shown and described.

DESCRIPTION

The FIGURE shows a front view of a display panel with graphic user interface, showing our new design.

The evenly-dashed outer lines in the FIGURE show a display panel and form no part of the claimed design.

The FIGURE includes solid grayscale coloring to show color contrast.
